UNITED STATES PATENT OFFICE

GARRISON BABCOCK, OF ROCHESTER, NEW YORK, ASSIGNOR TO THE TELECHRONOMETER COMPANY, OF ROCHESTER, NEW YORK, A CORPORATION OF NEW YORK.

TELEPHONE SYSTEM.

1,138,175.

Specification of Letters Patent.

Patented May 4, 1915.

Application filed March 6, 1911. Serial No. 612,582.

To all whom it may concern:

Be it known that I, GARRISON BABCOCK, of Rochester, in the county of Monroe and State of New York, have invented certain 5 new and useful Improvements in Telephone Systems; and I do hereby declare the following to be a full, clear, and exact description of the same, reference being had to the accompanying drawings, forming a part of 10 this specification, and to the reference-numerals marked thereon.

The present invention relates to telephone systems of the character which embody several substations on a party line, there being 15 located at each substation a message meter and a time meter to record each message and the number of time units consumed by the message, respectively, and has for its object to provide means whereby a subscriber 20 at any one of the substations may listen in to determine the condition of the line without actuating the message meter.

A further object is to provide a system wherein the normal condition of each substation is such that listening in on the line 25 is permitted, but conversation over the line is prevented, until the condition at the substation is changed by some operation of the subscriber, as, for instance, moving a switch 30 to open a circuit or in some other desirable manner.

To these and other ends the invention consists in certain improvements and combinations of parts all as will be hereinafter more 35 fully described, the novel features being pointed out in the claims at the end of the specification.

In the drawings: Figure 1 is a diagrammatic view illustrating a telephone system, 40 embodying the present invention; Fig. 2 is a detail view in side elevation of a switch in the short circuit including the transmitter, and push button for controlling the switch, and Fig. 3 is a detail view in transverse section of the switch operating push button and support therefor.

In systems of this type provision has been made to enable a subscriber to listen in to determine the condition of the line without 45 actuating the message meter, but it has been necessary for the subscriber to actuate a switch or some controlling element, in order to effect a condition at his station whereby he might remove the receiver from its hook 50 without causing actuation of the message

meter, and one objection to this has been that the subscriber will neglect to actuate the controlling means before removing the receiver from the hook, and in so doing he causes the message meter to be operated even 60 though a busy condition exists upon the line. It is, therefore, desirable to make an arrangement whereby each substation is normally in such a condition that its message meter will not be operated by removal of the 65 receiver from its hook. With this provision, a subscriber may listen in at any time, by simply removing his receiver, the message meter remaining inoperative until a controlling element is actuated to place the station 70 in a condition whereby conversation is permitted. Various means may be adopted for accomplishing the end set forth, and in the present embodiment, there is illustrated one form, in which the transmitter is short 75 circuited by the lowering of the receiver hook. The switch thus closed by movement of the receiver hook remains closed until opened by the subscriber.

In the system disclosed, to which the invention is applied, A, A' designate substations to which extend the line wires 1, 2 and B, B' are substations to which line wires 3, 4 extend from the exchange.

Line wires 1, 2 extend from the springs 80 5 and 6 of the jack J located at the exchange to the terminal posts 7 and 8, respectively, at the substation A, the line wire 2 having included serially therein at such substation 85 a time meter 9 adapted to be actuated by 90 current reversals in the line circuit, each reversal serving to advance the metering mechanism one unit. The post 7 is connected through the condenser 10 with the coils of the ringer 11, and also in parallel therewith 95 to the spring 12 of the hook switch H. The post 8 is connected with the other terminal of the windings 11 of the ringer and also to the coils 13 and 14, which are the setting 100 and actuating coils, respectively, of the message meter 15. The post 8 is also connected with the armature 16 of the ringer 11 and with the spring 17, adapted to be engaged by the spring 18 when the armature 19 of 105 the message meter 15 is moved to its set position. The post 8 is also connected with the pivotal point of the switch 21. The spring 18 is connected with the other terminal of the resetting coil 13 and also to the contact 20 and one terminal of the trans- 110

mitter T. The other terminal of the coil 14 is connected with a spring 22 adapted to be moved into engagement with the spring 23 by the armature 19 when such armature 5 is moved to its set position, the spring 23 being in turn connected with the spring 24 of the hook switch H.

The other terminal of the transmitter T is connected through the primary winding 25 10 of the induction coil with the spring 26 of the hook switch H. The springs 27 and 28 are connected together and also to the post 7. The secondary winding 29 of the induction coil is connected in circuit with the 15 receiver R. The transmitter T is also connected to the contact 21^a, which is adapted to be engaged by the upper end of the switch 21 when it is actuated, as a result of which the operation of such switch serves to short 20 circuit the transmitter and connect its terminals with the post 8, and thus with the line conductor 2. The switch 21 is arranged to be engaged and operated by a push button 21^b having recesses 21^c which permit vertical 25 movement in a guide on the bracket 21^d. The push button is provided with an enlargement 21^e adapted to engage a projection 21^f on the switch, and extends upwardly into contact with the receiver hook 21^g, so 30 that as the hook is lowered when the receiver is placed thereon, the push button is depressed, causing the contact 21 to be moved so as to close the circuit controlled thereby and thus short circuit the transmitter T. 35 When the receiver is again removed for the purpose of listening in to determine the condition of the line, the push button remains lowered, and the transmitter is short circuited, until the subscriber raises the push 40 button and opens the circuit to the transmitter.

The cord circuit employed in connection with the system embodying the invention, as shown, comprises a two-conductor cord, the 45 tip strand consisting of the sections 32 and 33, connected, respectively, with the tips 34 and 35 of the plugs P, P', and being separated by a condenser 36. The sleeve strand consists of the sections 37 and 38 connect- 50 ed, respectively, with the sleeves 39 and 40 of the plugs P, P', said sections being separated by a condenser 41. The sections 32 and 37 of the cord strands have connected therewith the relay magnets 42 and 43, 55 which are the supervisory relays of the answering end of the cord circuit, their other terminals being connected through wires 44 and 45 with the pivotal points of the armatures 46 and 47 of the relay 48. 60 The strands 33 and 38 of the cord circuit have connected therewith the windings of the supervisory relay magnets 50 and 51, the other terminals of which are connected by wires 52 and 53 with the positive and negative poles, respectively, of the battery 54.

The wire 52 has serially included therein the main or actuating winding 55 of the relay 48. Sections 33 and 38 of the cord strands extend through the ringing key K, by means of which current from the ring- 70 generator G may be impressed upon the calling plug P', in the usual manner. An operator's set O is connected with the strands 32 and 37 of the answering end of the cord to permit the operator to receive 75 the order from the calling subscriber.

The armatures 46 and 47 of the relay 48 normally rest against the back contacts 56 and 57, connected by wires 58 and 59 with the negative and positive poles, respectively, 80 of the battery 54. The wire 59 is also connected with the front contact 60 of the armature 46. The front contact of the armature 47 is connected by wire 62 with the positive brush 63 of the generator G', the negative brush 64 of which is connected with wire 58 and thus to the negative pole of the battery 54. The generator G' is designed so that it is operated only when its field magnet 65 is energized, and this is accomplished periodically in the following manner: The winding of the field magnet 65 is connected by wires 66 and 67 through the controlling switch 68 with the brushes of the generator 69, adapted to properly energize the winding of the field magnet 65 when the switch 68 is closed. The switch 68 is controlled by an electromagnet 70 connected by wires 71 and 72 with the positive and negative poles, respectively, of the battery 54. The wire 72 has included in it a commutator 73, rotated at a uniform rate by suitable time controlled mechanism, as a result of which the circuit through the magnet 70 is closed at regularly recurring intervals. 100

Assuming that the subscriber at substation A desires to call the exchange, he removes his receiver R from the hook switch H, thereby completing a circuit from battery 54 as follows: battery 54, wire 74, line relay 75' line wire 2, time meter 9, armature 16, contact 20, wire 75, wire 76, transmitter T, primary winding 25, spring 26, spring 27, wire 77, line wire 1, wire 78, and back to battery 54. Line relay 75' is thus energized, and closes a circuit from battery 54 through the line signal 79, indicating to the operator at the exchange that a connection is desired. The operator therupon inserts the plug P in the jack J corresponding to the signal 79, which energizes the cut-off relay 80 by the following circuit: battery 54, wire 59, contact 57, armature 47, wire 45, sleeve supervisory relay 43, cord strand 37, sleeve 39, ring 81 of jack J, winding of cut-off relay 80; wire 82, wire 78, and back to battery 54. 110

At the same time that the circuit just described is closed and battery 54 is cut off 130

from the line limbs 1 and 2, connection is made from the battery 54 through the transmitter T at the substation A over the following circuit: battery 54, wire 59, contact 57, armature 47, wire 45, sleeve supervisory relay 48, cord strand 37, sleeve 39 of the plug P, sleeve spring 6, line wire 2, time meter 9, post 8, armature 16, contact 20, wire 75, wire 76, transmitter T, primary winding 10 25, spring 26, spring 27, wire 77, post 7, line wire 1, tip spring 5, tip 34 of plug P, tip supervisory relay 42, wire 44, locking winding 49 of relay 48, armature 46, contact 56, wire 58, and back to battery 54. The winding 49 is so proportioned that the current flowing therethrough at this time is insufficient to attract the armatures 46 and 47. The operator thereupon, by means of her telephone set O, learns the connection desired 15 by the subscriber A, and, assuming that the subscriber B is wanted, inserts the calling plug P' in the jack J', connected with the line conductors 3 and 4, extending to the substation B. The operator thereupon actuates the ringing key K, thus connecting the generator G with the line limbs 3 and 4, and by a circuit similar to that traced for the substation A actuates the ringer 11 located at the substation B. The ringers 11 are all 20 so constructed that when current does not flow through them their armatures close the contacts 20 to short-circuit the terminals of the associated coils 13 of the message meters 15. Upon the response of the subscriber B 25 a circuit is closed through the line limbs 3 and 4 as follows: battery 54, wire 52, energizing winding 55 of relay 48, tip supervisory relay 50, cord strand 33, tip 35 of plug P', line wire 4, to and through the 30 apparatus at substation B by a circuit similar to that above traced for the substation A, returning by line conductor 3, sleeve 40 of plug P', cord strand 38, sleeve supervisory relay 51, wire 53, and back to battery 54. 35 As a result of the flow of current through the winding 55, the armatures 46 and 47 are attracted, thus connecting the supervisory relays 42 and 43 with the positive pole of the battery 54 and the positive brush of the 40 generator G' respectively. Assuming that at this time the circuit through the controlling magnet 70 is closed, the current in the line circuit is reversed as follows: battery 54, wire 59, contact 60, armature 46, locking winding 49, wire 44, tip supervisory relay 42, tip 34, tip spring 5, line wire 1, through the apparatus at the substation A in the reverse direction to that above traced, returning by line wire 2, sleeve spring 6, sleeve 45 55 39, sleeve supervisory relay 43, wire 45, armature 47, contact 61, wire 62, brush 63, armature of generator G', brush 64, wire 58, and back to battery 54. Thus the armature winding of the generator G' is included in 60 65 circuit at this time, but as the field circuit

is open only the ohmic resistance of the armature is included, and this is so small as to have practically no effect upon the current flow.

It is to be noted that the current sent out 70 over the line wires 1 and 2 previous to the energization of the relay 48 causes a current flow through the windings of the ringer 11 as follows: Line wire 2, time meter 9, post 8, coils of ringer 11, wire 83, spring 75 12, spring 28, wire 77, post 7, to the line wire 1.

It is to be noted that the direction of current flow through the coils of the ringer 11 is in the same direction during the signaling 80 of the exchange by the substation A and during the connection of the answering end of the cord to the line wires 1 and 2 before the called subscriber has responded. This direction of current flow through the ringer 85 11 is in a direction tending to move the armature 16 against the contact 20 to hold the armature 16 in its normal position, short-circuiting the resetting coil 13 of the message meter 15. When the relay 48 is 90 energized, and, as above described, current flows from the positive pole of the battery 54 out over line conductor 1, it will be observed that the direction of current flow through the ringer windings 11 is reversed, 95 as a result of which the armature 16 is moved away from the contact 20, opening the short-circuit across the terminals of the coil 13, which thereupon receives current in a direction to move the left-hand end of 100 the armature 19 downward to cause the armature to occupy its set position, for which position the springs 17 and 18 are moved into engagement with each other, thus again short-circuiting the coil 13 to 105 prevent further operation of the armature 19, until the actuating coil 14 is energized. It is to be noted that the motion above described of the armature 19 to its set position brings the springs 22 and 23 into engagement with each other, thus closing at one point the energizing circuit of the coil 14. The armatures 46 and 47 are held in their 110 attracted position as long as the switch hook at the substation B is in its raised or talking position, and even if the switch be subsequently moved to its normal position, opening the circuit through the supervisory relay 50 and the energizing winding 55, the locking winding 49 is so proportioned as to 115 retain the armatures 46 and 47 in their attracted position as long as the current flows through such locking winding, due to the switch hook at the substation A being in its upper or talking position.

After the relay 48 has been energized and during the time that the armatures 46 and 47 are held in their attracted position, the armature of the generator G' is retained in the circuit above described. The generator 120 125 130

4

G' is so constructed as to produce an electromotive force above twice that of the battery 54, and since its negative brush 64 is connected with the negative terminal of the battery 54, the electromotive force developed is partly consumed in charging the battery 54 during the intervals that the field 65 is energized, the remaining portion of the electromotive force developed by the generator G' being impressed upon the circuit in which its armature is connected as follows: Positive brush 63, wire 62, contact 61, armature 47, wire 45, relay 43, sleeve 39, sleeve spring 6, line wire 2, to and through the apparatus at the substation A, returning by line wire 1 to tip spring 5, tip 34, relay 42, wire 44, locking winding 49, armature 46, contact 60, wire 59, battery 54, wire 58, to the negative brush 64 of the generator G'. Thus, during the intervals that the field 65 of the generator G' is energized current is impressed upon the line-circuit in the same direction by the generator G' as the current was caused to flow through such line circuit by the battery 54 before the energization of the relay 48, from which it follows that the successive energization at recurring intervals of the field 65 of the generator G' reverses the direction of current flow periodically through the line conductors 1 and 2, and, therefore, causes actuation of the time meter 9. This meter therefore serves to register the length of time in telephones between the response of the called subscriber and the restoration of the apparatus at the calling substation to its normal condition by placing the receiver R upon the hook switch H. It is to be noted also that the current generated by the generator G' flows through the battery 54 in a direction opposed to the normal direction of current flow from such battery, and that therefore during the active intervals of the generator G' the battery 54 is charged.

The operation of my invention is as follows: Under normal conditions, when the receiver hook is down, the push button 21^b is lowered, and the switch 21 is closed, thereby short circuiting the transmitter. If the subscriber at substation A desires to call exchange, he removes his receiver from the hook, thus connecting the primary winding 25 in circuit with the line wires 1 and 2, and permitting him to listen in and determine if the line is in use. Were it not for the fact that the transmitter remains short circuited, switch 21 being closed, the armature 19 might be moved to its set position, assuming that the direction of current flow in the line 1, 2 were proper to cause this result, and this would cause a closure of the contacts 22 and 23, as a result of which the hanging up of the receiver would complete the circuit through the actuating winding 14; and even if the direction of current

flow at this time were not such as required to actuate the magnet 14, a subsequent reversal of the direction of current flowing the continued connection at substation A', would serve to actuate the magnet 14, and 70 advance the message meter 15 one unit. The time meter 9 is, of course, connected in circuit during the entire period of listening in, and thus a means is afforded for indicating the total length of time in telephones, or unit fractional parts of a minute, that the apparatus at substation A is operatively connected, whether as a result of instituting a connection or listening in on a connection already established. 75

As soon as the subscriber ascertains that the line is not busy, he moves the push button 21^b upwardly to open the switch 21, as a result of which connection is made from the battery 54 through the transmitter T, 85 and he is then able to advise the operator of the connection desired, and also to communicate with the respective substations when the operator effects the proper connection. When the subscriber is through talking, he hangs the receiver on the receiver hook, causing the push button to be depressed and to close the switch 21, thereby short circuiting the transmitter, so that further talking through the transmitter is prevented until the push button is manually operated to open the short circuit. 90

A further advantage to be attributed to the use of means such as described which are employed for rendering the message 100 meter inoperative and which is under the control of the subscriber, resides in the fact that frequently the connection which the subscriber calls for is completed by the "B-board" operator, and during the hours 105 when traffic is heaviest it not infrequently happens that the "B-board" operator inadvertently connects the calling subscriber with a busy line, which of course would result in operating the message meter at the 110 calling party's station. Again, the "B-board" operator might listen in on a trunk connection and thus operate the meter at the subscriber's station, but this is a contingency which would not occur in the event 115 said operator relied upon instructions received over the order wire. However by arranging the slide 21^b so that it is capable of manual operation independently of the switch hook as well as being automatically 120 movable by the latter, the subscriber may adjust it so as to cut out the message meter during the time the "B-board" operator is setting up the connection and until the called party answers. The adjustment of 125 the finger piece 21^b, either manually or by means of the switch hook, to close the contacts controlled thereby, also prevents the accidental operation of the subscriber's 130 message meter in the event two of them,

when connected, should for any reason oscillate their respective receiver hooks simultaneously, as is sometimes done in an attempt to signal the central office operator after 5 connection has been made.

I claim as my invention:

1. In a telephone system, the combination with telephone lines extending from substations to an exchange, a message meter 10 at one of the substations for registering the number of messages used, a receiver at the substation, a receiver hook, a shunt circuit having a pair of contacts and adapted when closed to render the message meter inoperative, an operating member controlled by the lowering of the receiver hook for closing said circuit, and adapted to be operated manually to open said contacts and permit the message meter to be operatively connected 15 to the line.
2. In a telephone system, the combination with telephone lines extending from substations to an exchange, a message meter at one of the substations for registering the number of messages used, a shunt circuit having contacts adapted when closed to render the message meter inoperative, said contacts being normally closed, and means for opening the same.
3. In a telephone system, the combination with telephone lines extending from a substation telephone set to an exchange, a message meter at the substation for registering the number of messages used, a shunt 25 circuit having contacts adapted when closed to create a condition for rendering the message meter inoperative when the line circuit is closed at the telephone set, and means for automatically closing said contacts when use 30 of the telephone set is discontinued.
4. In a telephone system comprising line wires extending from a central office to a plurality of substations and a telephone instrument set embodying a transmitter and a receiver located at each station, of metering devices at each of said stations, means at the central office for operating them and a branch circuit at each substation adapted to be closed to render the transmitter of instrument set and the meter at said station 45 temporarily inoperative.
5. In a telephone system, the combination with a central office, line wires leading therefrom and a substation telephone set connected thereto and including a transmitter, of a metering apparatus at the substation connected to the line wires, a branch circuit extending from the instrument set and adapted to short circuit the transmitter and 50 temporarily render the meter inoperative.
6. In a telephone system, the combination with a central office, line wires leading there-

from and a plurality of substations located thereon, each comprising an instrument set, of a metering apparatus at each substation 65 connected to the line wires and a branch circuit at each substation adapted to be closed to temporarily render the transmitter of its respective instrument set and metering apparatus inoperative.

7. In a party line telephone system, the combination with a plurality of telephone instrument sets, each comprising a receiver and a transmitter and a pair of line wires connecting said instrument sets, of a metering apparatus associated with each of said instrument sets, branch circuits adapted to be closed to short circuit the transmitters of the respective instrument sets and render the associated metering apparatus inoperative.

8. In a telephone system, the combination with telephone lines extending from a substation telephone set to an exchange, a message meter at the substation for registering the number of messages used and a controlling circuit for the meter, of means for creating a condition in said circuit for rendering the message meter inoperative when the line circuit is subsequently opened after use of the telephone set has been discontinued and for operatively connecting the message meter to the line when the latter is closed and the telephone set is in use.

9. In a telephone system, the combination with normally open telephone line circuits 95 extending from subscribers' stations to a central exchange, of message meters located at each subscriber's station, an operating circuit therefor adapted to be energized when the line circuit is closed, a shunt circuit 100 adapted to temporarily render the operating circuit inactive having a pair of contacts which are adapted to be closed when the line circuit is opened and remain closed until separated manually by the user of the 105 instrument.

10. In a telephone system, the combination with a normally open telephone line circuit leading from a subscriber's telephone instrument set to a central exchange office, said 110 instrument comprising the usual receiver hook, of a message meter associated with the instrument set having an operating circuit adapted to be energized when the line circuit is closed, a controlling circuit having a 115 pair of contacts adapted to be closed by the downward movement of the receiver hook and a finger piece by means of which the contacts may be opened.
